PUNCHED CARD REPRODUCER

Jiri Vodehnal, Prague, Czechoslovakia, assignor to
Arima, narodni podnik, Prague, Czechoslovakia

Application August 21, 1957, Serial No. 679,489

1 Claim. (Cl. 164—114)

The invention relates to a punched card reproducer with a correcting mechanism for reproducing cards from original or sample punched cards.

It is an object of the invention to provide a reproducer in which all of the punched data of the original card may be transferred to the punching mechanism, or any desired data of the sample card can be cancelled and which are then not transmitted to the new card, or other constant data can be introduced for subsequent punching in the new cards.

It is another object of the invention to provide a reproducer of the above mentioned type which permits the transfer of a limited number of data to various columns.

A further object of the invention is to provide a reproducer of the above mentioned type in which, by means of a special key-board, corrections of data from originally faulty cards and transfer of correct data to the punching mechanism may be effected.

Another object of the invention is to provide a reproducer which is adapted to effect the punching operation on the basis of creased or torn sample cards.

Still another object of the invention is to provide a machine which, in addition to providing normal reproductions of punched sample cards, accelerates several times the correction of faulty cards as compared with hitherto known machines.

According to one of the main features of the invention the data read or sensed from a punched card in the code thereof and entered in the same code in an adjustment box of the punching mechanism may be simultaneously corrected on a special decimal slide key-board mechanism in any desired columns prior to punching a new card.

According to a further feature of the invention the slide mechanism is adapted to decode data set in a decimal system to correspond with the code of the card, to cancel in the respective columns data read from the original or sample card and to directly set new data into the adjustment box of the punching mechanism.

The invention also comprises novel details of construction and novel combinations and arrangements of parts, which will more fully appear in the course of the following description. However, the drawings merely show and the following description merely describes preferred embodiments of the present invention, which are given by way of illustration or example only.

In the drawings:

Fig. 1 shows the reproducer according to the invention in a sectional view, the lower part being omitted,

Fig. 2 is a perspective view of part of the slide key-board with the adjustment mechanism,

Fig. 3 is a perspective view of a needle used for adjusting the slides,

Fig. 4 is an elevation view, partly in section, of a displaceable transfer chamber provided with Bowden cables and

2

Fig. 5 is a partial bottom plan view of the transfer mechanism.

The upper part of the machine shown in Fig. 1 serves for the feeding of punched sample cards which are to be reproduced. The sample cards are inserted into a feed hopper 1 of a known design used also in connection with other machines of this type. The control and drive of the upper part of the machine is effected by a shaft 2 extending transversely through the machine and driven by way of bevel gearing from a vertical driving shaft, which is not shown in the drawing.

The sample cards are fed successively between feed-
ing rollers 3, 4, 5, 6 which convey them between plates
7 and 8 until the card abuts against a stop 9. The read-
ing or sensing operation is carried out from above by
means of a vertically movable reading or sensing mecha-
nism 10 slidably mounted on a pair of guide columns.
All punched data on a card between plates 7 and 8 are
transferred by means of a transfer mechanism 11 to the
lower part of the machine.

After the reading or sensing mechanism has completed
its reading of the punched data on a card, the mechanism
10 is raised to an upper position, and the stop 9 is shifted
to release the sample card which is then conveyed by
rollers 12, 13, 14, 15 between ejecting rollers 16 and 17
which put it on top of a stack of cards on a plate 18
of an upper storage hopper 19 secured to the cover of
the machine.

The arrangement is such as to cause one sample card
30 to pass through the machine during each revolution of the
shaft 2. When a plurality of cards are to be punched ac-
cording to the pattern of a single sample card, the required
sample card may be retained in the reading-sensing
mechanism by pressing a control-button, whereupon any
35 desired number of equal reproductions may be punched.

The feeding hopper 1 is operated by a cam 20
mounted on the shaft 2 and transmitting motion to the
hopper mechanism by means of a lever 22 and a spring
21. The feed rollers 3, 4, 5 and 6 are also driven from
40 the shaft 2 by a suitable gearing (not shown). The
rollers 12, 13, 15 and 16 are provided with divided shafts
and are driven from both sides by separate transmission
gears (not shown) from the roller 5. The divided ar-
rangement of shafts permits the transfer mechanism 11
45 to be inserted into the machine, said mechanism 11 be-
ing actuated directly by the reading or sensing mecha-
nism 10.

The reading or sensing mechanism 10 is provided with
50 540 needles 23, which after having passed downwardly
through punched holes in a sample card and through
holes in a guiding plate 45 are secured by means of plates
24 in their lower position. The reading or sensing mech-
anism is driven downwardly to sense or read the punched
55 holes of the sample card by means of a pair of cams
on shaft actuating bent levers 27 and a pair of links (not
shown) whereas the upward movement is effected by two
pairs of springs 26.

The movement of the securing plates 24 is derived
60 from the movement of the reading or sensing mechanism
by means of a lever 25 which is connected, at one end,
to the plates 24 and, at its other end, follows a template
28. If no punched card is fed between the plates 7 and
8 of the mechanism, a lever 29 is then engaged by a con-
65 trol pin 30 and retain the lever 25 in a position where
the needles 23 are not secured in their lowered positions
by the plates 24. In this way the simultaneous transfer
of data corresponding to all 540 needles is prevented, as
such transfer could destroy the punching mechanism.
70 The card stop 9 is controlled by a cam (not shown)
mounted on the shaft 2 and actuating a link 31 which is
connected to a pair of levers 32 attached, by means of a

hollow pivot to the stop, and the latter is mounted for sliding motion on vertical pins 33.

In order to permit reproduction of torn or crushed cards an auxiliary device 35 is mounted between guiding plates 34 secured to the cover of the machine. The device 35 consists of two plates between which the damaged card is placed so as to be held flat, after which the assembly is inserted between plates 7 and 8 of the conveying device. This is made possible on the one hand by the storage hopper 19 being mounted for tilting movement on a rotatable hinge together with a part of the hood and further by depressing a lever 36 which, by means of bent levers 38, raises the feeding roller 17 and tilts the lever 32 so as to raise the stop 9. Further, depression of lever 36 causes a pair of links 37 to deflect levers 39 in the direction raising the plate 8 together with the feed rollers 14 and 15. The plate 8 is mounted for vertical movement on screws 40 carrying springs which press the plate 8 downwards. In order to prevent the device 35 inserted into the feed-mechanism from being ejected by the feed rollers during the rotation, suitable recesses are provided in the device 35 which keep the rollers out of frictional engagement therewith. Moreover, the device 35 is secured in its correct position by the stop 9, which snaps into a corresponding notch in the auxiliary device.

The central part of the machine receives the mechanism 11 which transfers all data to an adjustment device of the punching mechanism. The mechanism 11 is provided with 540 wires 41, which correspond to the needles 23 of reading mechanism and each carrying two collars. The upper collars of wires 41 abut against the guiding plate 45, whereas the lower collars serve as supports for pressure springs 42 tending to hold the wires in raised position. The wires are guided at their lower end in a plate 46. The mechanism 11 may be inserted into the machine on rails 44 and secured in its correct position by locks 43.

Instead of the above described transfer mechanism 11 having straight wires 41, a modified transfer mechanism provided with Bowden cables (Fig. 4) may be inserted into the machine, such modified mechanism permitting within a limited range the transfer of punched data from one point of the sample card to another point of the card to be punched. The modified mechanism of Fig. 4 consists of several five-column connecting pieces 47 and 48 linked together by means of Bowden cables 52. The connecting pieces 47 and 48 are secured merely by screws 49 and 50 and may easily be placed in any desired lateral positions relative to each other. The relative lateral positions of the top and bottom pieces 47 and 48 may be altered by simply changing the positions of spacing pieces 51. The pins 53 of the bottom connecting pieces 48 tend to be lifted by springs 54 so as to permit the transfer mechanism to be installed in and removed from the machine.

Inserted between the transfer mechanism 11 and the adjustment box of a punching mechanism 55 (Fig. 1) is a special correcting device 54 having pins 56 and which permits the data sensed from the sample card to be influenced by means of a slide key-board. The pins 56 correspond to the wires 41 of the transfer mechanism 11 of Fig. 1 or to the lower pins 53 of the alternative transfer mechanism of Fig. 4. Links 57, 58 are movable between the individual columns of pins 56, said links 57 and 58 being movable in the horizontal direction by key-board slides 59 and 60, which may be pulled out by the operator and also being movable in the vertical direction through a predetermined path upon each revolution of the machine.

The operation of the mentioned special correcting device 54 is apparent from Fig. 2. The slides 59 with links 57 correspond to the upper half of the punched card and the slides 60 and links 58 correspond to the bottom half of the punched card. By pulling out a particular slide, for example, by pulling out the slide 59

in column 9 of the upper half, to position No. 2, as shown in Fig. 2 the corresponding link 57 is adjusted with respect to the pins 56 so that a claw 57a of the adjusted link 57 upon downward movement of the device 54 depresses the pin corresponding to No. 9 while a socket 57b of the link depresses the pin corresponding to No. 1. In this way the number 2 is inserted into the adjustment box of the punching mechanism 55 in the code of the card. Pawls 61 are urged by flat springs 65 against ratchet teeth on the slides 59 to secure the slides 59 in their adjusted positions. The pawls are tilted by ramps provided on the slides at one end of the series of ratchet teeth in such a way that by means of links 63 they raise cancelling levers 67 (Fig. 1).

Upon movement of an axle 71 to the right, as viewed in Fig. 1, the cancelling levers 67, which are mounted on such axle, displace corresponding slides 76 of the adjustment box 55 to the right, so as to release pins 77 which have been depressed during the sensing or reading operation, and which are located in those columns corresponding to the slide 59 that has been pulled out. Each slide 60 corresponding to the bottom half of the card to be punched cooperates in a similar way with a pawl 62 acted on by a spring 66 and connected to a link 64 which, in turn, is connected to a cancelling lever 68. The levers 67 and 68 are slideable in comb-like guides 69 and 70.

The cancelling movement of the axle 71 occurs twice during each operating cycle. The first such movement takes place prior to the punching of a new card and this movement causes cancellation of those columns only, in which the slide 59 or 60 has been pulled out, and the second such movement takes place after the card has been punched in order to cancel all data then stored in the memory or adjustment box of punching mechanism 55. Upon the second cancellation movement of axle 71, an axle 79 is moved upward and shifts all levers 67 and 68 against protrusions on the slides 76. The drive of the cancellation axle 71 is effected from a cam on a shaft 81, by way of a two-arm lever (not shown), a link 75, a lever 74 extending radially from a shaft 73 and a lever 72 extending from shaft 73 and carrying axle 71. The drive of the lifting axle 79 is derived in a similar way, but from another cam on shaft 81 which actuates a mechanical transmission causing rocking of a shaft 80 having arms 78 projecting radially therefrom and supporting axle 79.

The described arrangement permits the cancellation of any desired columns by adjusting the slides 59 and 60. If the operator pulls the slides 59 and 60 to the position "m," the indication retained in the corresponding place of the adjustment box 55 is canceled before the card is perforated, thus preventing the indication from being transferred to the perforated card. When the slides 59, 60 are pulled out to one of the numbered positions "1" to "9," constant data are indicated on the corresponding places of the perforated card irrespective of the touched data. This permits quick repair of faultily perforated cards. Faulty cards detected by a verifying machine which checks the perforated cards are inserted into the top feed hopper 1. By depressing the trigger of a single revolution mechanism the first card is fed, read or sensed and laid away in the storage hopper 19, where it is clearly visible in the light of a lamp 82. A faulty column in the card may be marked and corrected with a pencil. The operator pulls out the respective slide 59 or 60 by means of a needle 89 (shown in Fig. 3) to indicate the correct value. When the machine is restarted, a new card is punched in the bottom portion according to the original card, but with the correction which has been carried out. At the same time a further faulty card may be read or sensed in the top portion of the apparatus.

The card punching device in the bottom part of the machine includes a box 83 having pins 77 slideable therein and spring urged upwardly against the corresponding pins 56 to return the latter to their original position during

the cancelling operation. The card to be punched is fed from a magazine 86 onto a matrix 85, which during a further revolution of the shaft 81 of the machine is raised together with the card against vertically movable punches 84. The punches 84 underlie vertically movable pins 88 associated with pins 77, and the punching operation is carried out only by those punches 84 which are supported by pins 88 secured against vertical movement by the associated pins 77. After the punching operation the punched card is led away to a storage hopper 87.

The feeding of cards in the upper and lower parts of the apparatus is arranged so that if a card fails to be fed, the machine is automatically stopped. The bottom part (not shown) of the machine comprises a motor with a worm gear, a starter, a mechanism for continuous operation and for single-revolution operation, the electrical installation and a waste receptacle.

I claim:

A sample punched card reproducer comprising a card feeding unit, a vertically displaceable reading unit for reading data from successive sample cards, a punching device for the cards to be punched, transfer means actuated in response to the reading of data by said reading unit and operative to concurrently introduce such data into the punching device, memory means in said punching device adapted to receive the data to be transferred, a correction device interposed between the transfer means

20

25

and said memory means of the punching device, said correction device having vertical flat pins for each punching position and for each column, horizontal slides and links adapted for co-operation with the vertical flat pins, 5 numerical scales provided on said slides for effecting selective correction of data to be transferred, a system of pawls engageable with said slides to secure them in individual digit positions, securing plates in said memory means, means operatively connecting said securing plates 10 to the pawls so that each securing plate is displaced when the related slide is pulled out to cancel the data of the respective column transferred by the transfer means prior to the punching of the card, means on each link to secure in its column the flat vertical pin corresponding in the 15 code of the punched card to the pulled out digit position of the related slide and means in said punching device by which the data set by the links of said correction device are punched in the card in the respective columns.
